Primary Examiner — Marie D. Fast Horse*(74) Attorney, Agent, or Firm* — Baker & McKenzie LLP(57) **CLAIM**

The ornamental design for a ceiling fan housing with light fixture, as shown and described.

DESCRIPTION

FIG. 1 is a perspective view of a ceiling fan housing with light fixture in accordance with my design;

FIG. 2 is a top plan view of the ceiling fan housing with light fixture in accordance with my design;

FIG. 3 is a bottom plan view of the ceiling fan housing with light fixture in accordance with my design;

FIG. 4 is a front elevation view of the ceiling fan housing with light fixture in accordance with my design;

FIG. 5 is a rear elevation view of the ceiling fan housing with light fixture in accordance with my design;

FIG. 6 is a left-side elevation view of the ceiling fan housing with light fixture in accordance with my design; and,

FIG. 7 is a right-side elevation view of the ceiling fan housing with light fixture in accordance with my design. The broken lines showing the fan blades, down rod, and ceiling mount depict environmental subject matter only and form no part of the claimed design.

All other broken lines depict portions of the ceiling fan housing with light fixture that form no part of the claimed design.

1 Claim, 5 Drawing Sheets(56)
